UNITED STATES PATENT OFFICE.

GEORGE H. FULLER, OF PAWTUCKET, RHODE ISLAND.

MANUFACTURE OF JEWELERS' FINDINGS.

SPECIFICATION forming part of Letters Patent No. 323,927, dated August 11, 1885.

Application filed December 17, 1884. (No model.)

To all whom it may concern:

Be it known that I, GEORGE H. FULLER, of the town of Pawtucket, in the county of Providence and State of Rhode Island, have invented new and useful Improvements in the Manufacture of Jewelers' Findings; and I do hereby declare that the following, taken in connection with the drawings which accompany and form part of this specification, is a description of my invention sufficient to enable those skilled in the art to practice it.

My invention relates to the joint of articles of pin-jewelry by which the pin-stem is attached to the pin-bar; and it consists, essentially, of an improvement upon the invention for which Letters Patent of the United States No. 286,601 were granted to me October 16, 1883, whereby is secured greater strength, durability, and economy in those articles of jewelry to which it is applied.

Referring to the drawings, Figure 1 is a perspective of the cup-joint from which is formed the journal-bearings, by the prick-punching process, of the pin-stem. Fig. 2 represents the pin-stem, pin-bar, and holder combined. Fig. 3 represents various modifications of Fig. 1, in which the base of the holder is shown in different configurations; and Fig. 4 is a vertical section of the pin-joint taken 30 through the line *xx*, Fig. 2.

Similar letters of reference indicate corresponding parts throughout the various figures.

The cup-joint in jewelers' findings represented by Fig. 1, and the modifications shown in Fig. 3, is an elongated small metallic cup, *b*, elevated above the flanged base *a*, cut from or struck up from a piece of sheet metal, the operation producing the article in the shape required. It will be seen that the diameter 40 of the base exceeds the diameter of the cup, in-

asmuch as the base is a flange of the cup. The flange is the part of the cup-joint which is soldered to the pin-bar. By uniting the cup-joint to the bar upon a base broader than the direct bearings of the pin gives stability to the article, because the resistance to any purchase made on the pin-stem would be directed in a line outside the cup—a condition that favors strength and permanence.

The modifications of the cup-joint shown in Fig. 3 illustrate some of the many ornamental forms that may be given to the flange *a*.

After the cup-joint is attached to the bar *c*, the pin-stem *d* is inserted into the cup *b*, and the cheeks or opposite sides are prick-punched or otherwise shaped to make a journal-bearing for the pin-stem.

Heretofore the cup-joint was constructed without the flange *a*, and provided with a base, conical in form, whose diameter was even less than the cup-joint itself. The limited surface to which the solder could be applied to attach the cup-joint to the pin-bar in making the union required precision and careful workmanship, which entailed increased expense to the product.

Having described my invention, I claim as new and desire to secure by Letters Patent—

1. In jewelers' findings, a cup joint consisting of an elongated metallic cup having a flanged base formed from a piece of sheet metal, for the uses set forth, and substantially as specified.

2. The combination of the cup *b*, the flange *a*, bar *c*, and pin-stem *d*, substantially as specified.

GEORGE H. FULLER.
